UNITED STATES PATENT OFFICE

163,167

PLASTIC UPHOLSTERY MATERIAL OR THE LIKE

Clifford D. Couch, Scarsdale, N. Y.

Application November 27, 1950, Serial No. 13,142

Term of patent 14 years

(Cl. D87—3)

To all whom it may concern:

Be it known, that I, Clifford D. Couch, a citizen of the United States, residing in Scarsdale, in the county of Westchester and State of New York, have invented a new, original, and ornamental Design for a Plastic Upholstery Material or the like, of which the following is a specification, reference being had to the accompanying drawing, forming part thereof.

Fig. 1 is a face view of a plastic upholstery material or the like showing my new design. A design unit is outlined by broken lines and is repeated over the plastic upholstery material or the like as indicated.

Fig. 2 is a face view of a portion of the plastic upholstery material or the like shown in Fig. 1, said portion being located near the lower right hand corner of said figure.

I claim:

The ornamental design for a plastic upholstery material or the like, substantially as shown and described.

CLIFFORD D. COUCH.
